UNITED STATES PATENT OFFICE

2,001,428

STRUCTURAL UNIT

Edward H. McClintock, West Springfield, Mass.

Application August 3, 1934, Serial No. 738,313

6 Claims. (Cl. 189—40)

This invention relates to an improved structural unit of the composite type for use in floor and wall constructions.

The object of the invention is to provide a structural unit, in which a nailing medium, such as wood or any other material suitable for the purpose, may be effectively clamped and laterally compressed between two angular bars of metal in a novel manner by simple and relatively inexpensive means, the unit having the qualities of light weight combined with strength and presenting one or more nailing surfaces.

The invention also contemplates floor and wall constructions of novel form in which these structural units are employed, either as nailing screeds or load bearing members, such as beams or studs and struts.

The invention has for a further object the provision of a floor construction embodying a plurality of these structural units, used to support a floor, in combination with a container for fire-proofing, insulating or sound deadening or other material, such container taking the form of a pan of sheet metal, supported by and between adjacent units in a novel manner.

These and other objects will more particularly appear as the detailed description proceeds and will be pointed out in the appended claims.

The invention will be described with reference to the accompanying drawings, in which:

Fig. 1 is a cross sectional view of a structural unit embodying my invention;

Figs. 2 and 3 are sectional elevational and cross sectional views, respectively, showing a floor construction including a plurality of said units;

Fig. 4 is a fragmentary side view of the pan shown in Fig. 2;

Fig. 5 shows the application of the units to a slightly different form of floor construction; and

Fig. 6 shows the application of the units to one form of wall construction.

Referring to these drawings and particularly to Fig. 1; the structural unit is composed of a pair of angle irons 10 between which wood, or any other suitable nailing medium, is received and compressed in a novel and advantageous manner. As shown, a strip of wood 11 is employed as the nailing medium and this strip is of substantially square cross section, modified by chamfering the edges, leaving diagonally opposite flat surfaces 12 exposed between the angle irons and, preferably also, diagonally opposite flat surfaces 13, adjacent the fillets of the angle

irons. The cross sectional shape of the strip 11 need not necessarily be square as shown. It may be modified, as desired, to meet various conditions and expose a greater or less width of the strip between the angle irons. It may also be modified, as will later appear, to cooperate with angle irons in which the angle between the two legs is greater or less than ninety degrees. Also, the legs of the angle irons need not be of equal length, as will be clear from Fig. 6, where the space between the lower corners of the two angle irons is less than that between the two upper corners. So also, it will be seen from Fig. 6 that it is not always necessary to chamfer the edges, as described. The main essential is that the strip 11 have four faces 14 which present two oppositely disposed wedge-shaped portions adapted to be engaged one by each of the angle irons.

These angle irons are secured together and the wood, or other filler, clamped and compressed therebetween in a simple and inexpensive but very effective manner by a wedge-like action. Considering any one section of the structural unit, a single bolt such as 15 is used for the purpose. According to prior art methods two bolts have been used for clamping a wood piece between two angle irons. In such case, the bolts are located at right angles and each passes through one leg of one angle iron and the opposite leg of the other angle iron. No wedge like action can result with such an arrangement. According to my invention, a single bolt is used, such bolt passing diagonally across the wood or other strip 11 and through the corners of the two angle irons. As shown in Fig. 3, each angle iron has a slot 16 which may be formed by a single punching operation, and made of sufficient depth so as to leave a rectangular hole 17 at the corner of the angle iron through which the bolt may be passed. The vertical walls of the slot 16 receive between them, and closely fit two opposite sides of the nut 18 and hold it against rotation while the screw-slotted head 20 of the bolt is turned. The slot 16 may also receive a washer, such as 19, or other members such as those shown in Fig. 6. The bolt pressure, applied to each angle iron in the way shown may be resolved into two forces, one acting squarely against each of the pair of engaged faces 14 of the strip 11. The wood strip is thus compressed in a very effective manner by a single bolt. In the particular example shown, a bolt pressure of 1000 lbs. may safely be obtained and this pressure may be resolved into separate forces of 707

<p

lbs. acting against each wedge face 14. Necessarily by decreasing the angle of the wedge an increase in the pressure on the wedge faces can be obtained using the same bolt pressure.

5 These structural units, in lengths to suit, are capable of being used in a variety of ways. For example, they may be used as nailing "screeds" in connection with concrete floors or walls, or as beams or columns in floor or wall constructions, 10 respectively. In each case, the structural unit is mounted with the legs of the angle irons disposed at an angle to the floor or wall, as the case may be, and the bolts 15, which are applied at suitable intervals throughout the length 15 of the unit, parallel such floor or wall.

In Figs. 2 and 3, the invention is shown as applied to a floor construction. In this embodiment of the invention, steel joists 21, each in itself affording the requisite strength and yet 20 of light weight, are interconnected at suitable intervals by these structural units. Each unit rests upon the upper flanges 22 of the steel joists and is secured thereto in any suitable manner, as for example by a wood screw 22', passed 25 through each said flange and threaded into the overlying strip 11, entering the lower flat face 12 thereof. The floor boards 23 rest upon the exposed upper faces 12 of the units and are nailed thereto, as indicated at 24.

30 Another feature of the invention consists in combining with these structural units a sheet metal pan which serves as a container for any material desired for the purposes of fire-proofing, sound-deadening, or insulation, such as the rock wool 40, for example. This pan, designated 26, is of a width such as to span the space between two adjacent units and of a depth at least no greater than the width of the unit, measured 35 across the faces 12 thereof. The pan has downwardly converging sides 27, sloped to conform to the slope of the upper legs of the two angle irons and is, or may be, supported solely by its weight resting on such faces. To hold these pans 40 against displacement, I provide in the sloping sides a series of struck out lips 28, substantially 45 square in shape and located one adjacent the head or nut of each bolt 15. The striking out of each lip 28 leaves a square hole 29, into which the head 20 of the bolt 15, its washer 19, or the nut 18 partially enters. The lips 28 underlie such 50 heads, washers or nuts as the case may be. The pan is put in place by first engaging one sloping side 27 with one structural unit, causing the lips 28 to slide beneath the nuts or heads of the bolts 15. Then the pan is swung downwardly as far 55 as possible toward the illustrated position, or until the lips 28 strike the heads or nuts of the bolts 15 of the other structural unit. Then the lips 28 are pried down by a screw driver or other 60 tool until they slide into place between such nuts or heads. The pan is thus simply but effectively held against displacement in longitudinal, lateral and vertical directions.

Another embodiment of the invention is shown 65 in Fig. 5. This is a first floor construction, where the wood flooring 23 is to be applied just above a concrete floor, designated 30. Here the structural units are interposed between the parts 23 and 30 resting, as for example, on pads of mortar 70 31 spread on the concrete. The structural units are tamped down in these beds of mortar so as to lie level. They are thus partially imbedded in the mortar. In some cases, the units may be completely imbedded in a concrete floor 75 or wall with the upper faces 12 of the strips 11

flush or just slightly above the top surface of the concrete. In this case as well as in the example shown in Fig. 5, it may be desirable to protect the wood from moisture and for this purpose it may be impregnated with creosote, painted with tar or otherwise treated before being clamped between the angle irons. Also, a metal strip, such as 33, may be laid over the two lowermost faces 14 of strip 11 and the extreme lower face 12 thereof and clamped in place as shown. In this 10 case, I may use the pan 26, applied to the structural units in the same way, for the purpose of receiving fire-proof or insulating material. The floor is thus protected against dry rot because dampness cannot penetrate from the underlying 15 concrete to cause it and it is insulated against cold from the underlying concrete, which in this case is laid directly on the ground.

A further variation in the floor construction 20 consists in imbedding the structural units in concrete, using them solely for the purpose of nailing screeds.

The invention is also applicable to wall constructions, one example of which is illustrated in Fig. 6. Here the structural units are mounted 25 upright and used as struts or studs. They are of the same general form as described except that the legs of each of the angle irons 10' are of different lengths. In Fig. 6, the interior wall surface is formed by sheets 35 of metal extending 30 between adjacent units and having opposite vertical edges turned at acute angles, as at 35' to lie between the wood strip 11' and the angle irons 10'. In order that adjacent sheets 35 may abut, as shown, the inner legs of the angle irons are 35 made longer and the lower corner of the strip 11' is left square. The interior surface of these sheets of metal may be painted or treated in various ways to provide a decorative finish, as by graining them to resemble wood, by stippling 40 them and so forth. It is to be noted that the sheets 35 will be drawn taut between the angle irons 10' when the bolts 15 are tightened. The exterior surface may consist of sheet metal or other siding 36, nailed as indicated at 37 to the 45 wood strips 11'. In this construction, girts 38 or any suitable form are shown as interconnecting adjacent units, the ends of such girts being clamped in place by the bolts 16. The space between the units and the walls 35 and 36 may be 50 filled with insulation 39.

It will be noted that the strip 11 of wood or equivalent material may be very effectively compressed between the angle irons. It is held by pressure applied to and distributed equally on 55 all four of its main faces and only such relatively small areas of the strip are exposed as are necessary to receive the nails or other fastenings employed. It is very important that the strip 11 be laterally compressed to prevent it from splitting when nails are driven into the same. Also, when these units are used in concrete as screeds, the wood is prevented from swelling when the concrete is poured and from subsequently shrinking when dry. A wooden strip, used as a screed and imbedded in concrete and devoid of the compression afforded by the angle irons, would swell and later shrink and become loose. A loose "screed", especially if of small size, is liable to crack when a nail is driven into it. Thus, such a screed affords a poor means in which to firmly fasten the floor boards.

When the strips 11 are coated with preservative, such as tar, creosote or the like, this preservative is protected by the angle irons 10.

The invention affords a composite structural unit having strength combined with lightness and affording one or more nailing surfaces. The floor construction of Figs. 2 and 3, excluding the 5 steel joists and flooring as is customary but including the pan 26 and assuming it to be filled with rock wool insulation 40, has the remarkably low weight of four pounds per square foot or about half the weight of the lightest commercial 10 form of floor construction with which I am familiar. The construction is likewise relatively inexpensive, being made up as it is, from a square strip of wood, a relatively few bolts and angle bars of standard form punched to receive 15 the bolts. The construction forms an excellent substitute for wooden joists and lends itself well to fire-proofing, water-proofing, insulating or sound deadening.

The invention has been disclosed herein, in an embodiment at present preferred, for illustrative purposes but it is recognized that the invention is susceptible to many variations and capable of being embodied in various forms differing specifically from the one herein disclosed. 25 It is therefore desired to have the scope of the invention defined by the appended claims rather than by the foregoing description.

What I claim is:

1. A composite structural unit, comprising, a 30 strip of nailing medium presenting a pair of opposed wedge-shaped portions, a pair of load-bearing angle bars of metal one for each said wedge-shaped portion, each angle bar having the legs thereof engaged one with each of the two 35 faces of its wedge-shaped portion and throughout substantially the entire length thereof and having the corner of the angle bar located adjacent the narrow part of the wedge, and means acting on the angle bars along the corners thereof for drawing said bars together to compress said strip therebetween.

2. A composite structural unit, comprising, a 45 strip of nailing medium presenting a pair of opposed wedge-shaped portions, a pair of load-bearing angle bars of metal one for each said wedge-shaped portion, each angle bar having the legs thereof engaged one with each of the two 50 faces of its wedge-shaped portion and throughout substantially the entire length thereof and having the corner of the angle bar located adjacent the narrow part of the wedge, and fastening devices for drawing said angle bars together to clamp said strip therebetween, each said device extending through the corner of each angle bar and through 55 said wedge portions.

3. A composite structural unit, comprising, a 60 strip of nailing medium presenting a pair of opposed wedge-shaped portions, a pair of load-bearing angle bars of metal one for each said wedge-shaped portion, each angle bar having the legs thereof engaged one with each of the two faces of its wedge-shaped portion and throughout substantially the entire length thereof and having the corner of the angle bar located adjacent the

narrow part of the wedge, and means acting on the angle bars along the corners thereof for drawing said bars together to compress said strip therebetween, the outer end of at least one leg of each angle bar being spaced from the corresponding leg of the other angle bar to expose therebetween a portion of said nailing medium. 5

4. A composite structural unit, comprising, a strip of nailing medium presenting a pair of opposed wedge-shaped portions, a pair of load-bearing angle bars of metal one for each said wedge-shaped portion, each angle bar having the legs thereof engaged one with each of the two faces of its wedge-shaped portion and throughout substantially the entire length thereof and having the corner of the angle bar located adjacent the narrow part of the wedge, and fastening devices for drawing said angle bars together to clamp said strip therebetween, each said device extending through the corner of each angle bar and through said wedge portions, the outer end of at least one leg of each angle bar being spaced from the corresponding leg of the other angle bar to expose therebetween a portion of said nailing medium. 10 15 20 25

5. A composite structural unit, comprising, a strip of nailing medium presenting opposed wedge-shaped portions and an intervening portion into which nails or the like may be driven, a pair of load-bearing angle bars of metal, one for each said wedge-shaped portion and each 30 presenting two legs radiating from a common corner edge, the said legs of each bar being angularly spaced to fit the angle of its wedge-shaped portion and being engaged one with each of the two faces of such portion, and fastening devices 35 extending through the corner edges of the angle bars and through said wedge-shaped portions in bisecting relation for drawing said bars together and compressing said medium therebetween by pressures equally distributed on each of the four 40 faces of the two wedge-shaped portions. 40

6. A composite structural unit, comprising, a strip of nailing medium presenting opposed wedge-shaped portions and an intervening portion into which nails or the like may be driven, a pair of load-bearing angle bars of metal, one for each said wedge-shaped portion and each 45 presenting two legs radiating from a common corner edge, the said legs of each bar being angularly spaced to fit the angle of its wedge-shaped portion and being engaged one with each of the two faces of such portion, and fastening devices 50 extending through the corner edges of the angle bars and through said wedge-shaped portions in bisecting relation for drawing said bars together and compressing said medium therebetween by pressures equally distributed on each of the four 55 faces of the two wedge-shaped portions, the outer edge of at least one leg of one angle bar being spaced from the outer edge of the corresponding leg of the other angle bar to expose said intervening portion of said medium. 60

EDWARD H. McCLINTOCK.
